UNITED STATES PATENT OFFICE.

JOHN H. YOUNG, OF PELHAM, NEW YORK.

IGNITING ATTACHMENT FOR LAMPS.

1,048,258.

Specification of Letters Patent. Patented Dec. 24, 1912.

Application filed September 4, 1912. Serial No. 718,451.

To all whom it may concern:

Be it known that I, JOHN H. YOUNG, a citizen of the United States, residing at Pelham, in the county of Westchester and 5 State of New York, have invented a new and Improved Igniting Attachment for Lamps, of which the following is a specification.

This invention relates to an igniting attachment more particularly intended to light automobile lamps, the device being so constructed that it can be readily attached to a conventional lamp burner, without requiring any fitting or alteration of the same.

15 In the accompanying drawing: Figure 1 is a front view partly broken away of a lamp provided with my igniting attachment; Fig. 2 an enlarged longitudinal section of the igniting device on line 2—2, Fig. 20 4; Fig. 3 a side view thereof, and Fig. 4 a horizontal section.

The igniting attachment comprises essentially a plate or bracket 10, having a curved jaw 11, adapted to straddle the stem 12, of 25 an acetylene or other burner 13. Opposite said jaw there is tapped into plate 10, a screw 14, which may be projected against said stem, so that the plate may be readily clamped in position at a suitable distance 30 below the burner.

Through an aperture 15 of plate 10, there extends loosely a vertically movable tubular stem 16, which normally descends by its own weight to its lowermost position, so as 35 to be suspended from the plate (Fig. 2). The upper end of tube 16 is forked as at 17, and within the fork there is pivoted a milled or serrated steel wheel 18. Within tube 16 there is contained a block of pyrophorous 40 material 19, which is frictionally held against wheel 18 by a spring 20, which bears with one end against said block, and with its other end against a threaded follower 21, tapped into the lower end of the tube. Thus 45 by turning the follower, the pyrophorous block 19 will be spring-pressed against wheel 18, and may be raised from time to time when worn. In order to hold tube 16 from turning, it is provided with a flattened 50 face 22 engaged by a set screw 23 tapped into plate 10.

To ignite the burner, tube 16 is raised to

bring wheel 18 into horizontal alinement with burner 13. Wheel 18 is now given a quick turn by the finger, to friction against 55 block 19 and thus produce a spark that will ignite the gas, after which the tube is released, to descend and resume its normal position, so that the sparking mechanism becomes distanced from the flame. 60

It will be seen that the igniting device can be readily coupled to a conventional burner without requiring the latter to be in any way changed, and that it provides convenient means for lighting an automobile or 65 similar lamp in a quick and convenient manner.

I claim:

1. An igniting attachment for lamps, comprising a bracket, adapted to be removably 70 secured to a burner, a vertically movable tubular stem engaging the bracket, a pyrophorous block within the stem, and a wheel pivoted to said stem, and adapted to frictionally engage said block. 75

2. An igniting attachment for lamps, comprising a bracket adapted to be removably secured to a burner, a vertically movable tubular stem engaging the bracket, a pyrophorous block within the stem, a spring engaging the block, a follower tapped into the block and engaging the spring, and a wheel pivoted to the stem and adapted to frictionally engage the block. 80

3. An igniting attachment for lamps, comprising a bracket having a curved jaw adapted to straddle a burner, a set screw tapped into the bracket and adapted to hold the burner against said jaw, a stem vertically movable in the bracket, and a sparking 90 device carried by the stem.

4. An igniting attachment for lamps, comprising a bracket having a curved jaw adapted to straddle a burner, a set screw tapped into the bracket and adapted to hold 95 the burner against said jaw, a stem vertically movable in the bracket and having a flat face, an additional screw tapped into the block and engaging said face, and a sparking device carried by the stem.

JOHN H. YOUNG.
